UNITED STATES PATENT OFFICE.

EDWARD M. CRANDAL, OF CHICAGO, ILLINOIS.

LINK-FENCE.

SPECIFICATION forming part of Letters Patent No. 240,388, dated April 19, 1881.

Application filed February 28, 1881. (No model.)

To all whom it may concern:

Be it known that I, EDWARD M. CRANDAL, of Chicago, in the county of Cook and State of Illinois, have invented certain Improvements in Link-Fences, of which the following is a specification.

In the Letters Patent to me dated November 28, 1876, No. 184,844, there is described a fence composed of open-ring links formed of a 10 length of wire doubled together so as to form an eye out of the center of the length and having its two ends barbed or pointed, the barbed points of each link being passed through the eye of its neighbor link, and then twisted and 15 interlocked, so as to prevent withdrawal, the portion of the link between the eye and the barbed ends being left open.

In the present invention, which is an improvement upon that shown in said patent, I 20 employ a ring-link having an eye at one end formed by the doubling of the length of wire and barbed points at the other end; but instead of leaving the central portion open, as in said former invention, I twist it after the manner 25 of ordinary fence-cables; and I also lock the links together in a stronger and different manner from the previous patent.

The accompanying drawings show at Figure 1 a section of my improved fence, and Fig. 30 2 shows a portion thereof not completely formed.

In said drawings, A A represent the links, which are entirely alike. They are formed of pieces of wire pointed at both ends, a a, and 35 doubled at the center, so as to bring said points together and to form the bend or eye a'. Said ends or points are inserted within the bend a'

of the adjoining links, and are then bent back and around said part a', passing, in so doing, through or between the sides of the link of 40 which they themselves are a part, thus forming eyes a² in each of the ends a surrounding the bend a' of said neighbor link, and sustaining each an equal amount of the strain. The ends are next bent at right angles laterally to 45 the fence, and so as to lie down upon the sides a³ of the link. There is formed in this manner a firm lock of each link to its neighbor, which will not permit separation and will resist any strain which the continuous parts of the links 50 are capable of withstanding.

The link is completed by twisting it between its ends, as clearly illustrated. This prevents any tendency of the links to telescope one within the other.

With links constructed after my present invention the fence has all the strength of the continuous wire with added flexibility.

Fig. 1 gives two views of the coupling-joint, and Fig. 2 contains a view thereof which is 60 the reverse of the left-hand one in Fig. 1.

I claim—

The link-fence composed of the doubled and twisted links coupled together by bending the points of one through and around the eye of 65 its neighbor, the bend of the points being continued until they have passed through their parent link and are spread laterally, so as to rest upon the sides thereof, substantially as shown.

EDWARD M. CRANDAL.
